UNITED STATES PATENT OFFICE.

DANA S. LEE, OF ST. LOUIS, MISSOURI.

BRAKE-LEVER CIRCUIT CLOSER FOR AUTOMOBILE THEFT SIGNALS.

Application filed November 7, 1919. Serial No. 336,334.

To all whom it may concern:

Be it known that I, DANA S. LEE, a citizen of the United States, residing at St. Louis, Missouri, have invented certain new and 5 useful Improvements in Brake-Lever Circuit Closers for Automobile Theft Signals, of which the following is a specification containing a full, clear, and exact description, reference being had to the accompanying 10 drawings, forming a part hereof.

My invention consists in the novel construction and combination of parts herein-after particularly described and distinctly claimed.

15 The object of my invention is to provide an improved brake-lever circuit-closer, to be used as a part of the theft-signal for automobiles, whereby the stealing of automobiles having my invention applied thereto, will 20 in a great measure be prevented, inasmuch as an alarm will be sounded (or otherwise made) as soon as the would-be thief moves the brake-lever (or other lever of the automobile) in starting the car.

25 A further object of my invention is to provide an improved brake-lever circuit-theft-signal mechanism for automobiles, which shall be set for operation, as well as released, by the single movement of the 30 owner's lock-key.

In the drawings,

Fig. 1 is a perspective view of a portion of an automobile having my invention applied thereto.

35 Fig. 2 is a side-elevation of a portion of the brake-lever and its sector, on an enlarged scale, having the electric contacts in position for closing and breaking an electric circuit through the contact in the owner's 40 lock, the electrical-connections being shown diagrammatically, and

45 Fig. 3 is a plan-view, partly in section, of the brake-lever sector arrangement for making and breaking the circuit on the alarm-bell or other alarm-device.

The numeral 1 designates the casing of the owner's lock, which is provided with a common key 2, and is attached to the dash or cowl 3 by means of common screws or bolts 50 (not shown), so that by turning said key downwardly an electrical-contact will be made by the inner web of said key depressing (or otherwise moving) a movable-contact device 4 into contact with a fixed-contact 55 tact 5 in circuit with a suitable battery 6

(or other source of electricity). The current passes through the conducting-wires 7, two movable contacts 8 carried by the brake-lever sector 9, the brake-lever 10, and an alarm-bell, gong, common electric-horn, or 60 common electric-lights when an alarm is to be made after dark, the said alarm-device being designated by the numeral 11.

The casing of the owner's lock 1 is connected to said conducting wires 7 at 12, so 65 that it is in circuit with the said parts, as shown in Fig. 2. Said lock 1 is of the usual well-known construction, having a bolt that is moved by said key 2.

Moving said key in one direction throws 70 said movable contact 4 of the lock into contact with the said fixed contact 5, while moving said key in the opposite direction breaks the contact between said parts 4 and 5. It should be explained that the said lock-casing 75 1 is insulated from the automobile frame; also that the curved line which is shown upon the interior of the lock, in Fig. 2, designates a common lock-spring that is used in returning the said movable contact-device 4 to its normal position, and in retaining same thereat, after said contact-device has been moved into contact with the 80 said fixed contact 5.

The bolt of the lock, above referred to, is 85 not necessarily the said movable contact-device 4, as many well-known locks can be used with bolts and other parts intact; but the said contact-device should, of course, be applied to such locks as an addition to them. 90

In the present form of my invention, I fix the two movable-contacts 8 in a special sector-plate 14 attached to the usual sector-plate 15 by means of screws or bolts 16.

Said contacts 8 are insulated from said 95 sector-plates 14 and 15, and from each other, by means of insulating-tubes 17 having a shoulder or flange 18 upon the interior of the end that is nearest the said lever 10, and set in suitable holes bored in the said sector- 100 plates.

A head of flange 19 upon the outer end of each of said contacts 8 prevents said contacts from being pushed too far within said tubes, while a shoulder or flange 20 on the 105 inner portion of said contacts limits the outward movement of said contacts.

Behind each of said contacts 8, within said tubes 17, is a suitable spring 21, the outer ends of which are in contact with the 110

inner ends of said contacts, while the opposite ends of said springs rest against a fixed part or stop 22.

The said fixed part 22 is made of metal, 5 and is in circuit with the said movable-contacts 8 through said springs 21.

One terminal of said wires 7 is connected to one of the said fixed parts 22, so that the movable-contact 8 of that fixed part will be 10 in circuit.

The other one of the movable-contacts 8 (which is above or below the one last-mentioned) also has its fixed part 22 connected to one terminal of one of said wires 7, so 15 that both of said movable-contacts will be in circuit with the said lock-casing 1, the battery 6, the two movable-contacts 8 on the brake-lever sector, and with the said alarm-device 11.

20 The said casing 1 of the owner's lock, the batteries 6, and the said bell 11, are preferably concealed under the cowl or hood of the automobile.

A strong hardened-steel tube, or flexible 25 metallic-cover 23, is used to protect the said wires 7 in their passage from the parts under the cowl or hood to the sector plate 14 and the sector-plate 15, said wires passing through said tube, as shown in Fig. 1, and 30 said tube having a flange 24 on the end which is attached to said sector-plate 15.

Said flange 24 is fixed to said sector-plate 15 by means of rivets or screws 25.

By thus locating said wires 7 in said tube 35 23, the wires are protected against cutting or breaking by a thief, so that in order to cut or break said wires it will be necessary for the thief to use a hammer in breaking or removing said tube, which will attract 40 attention by the sound of the blows of said hammer, and the thief will probably be thereby detected in his nefarious work.

The operation.

45 The operation of my invention is very simple, as when a thief attempts to steal an automobile fitted with my invention, and with the parts in the positions shown in

Figs. 1 and 2, the forward movement of the brake-lever 10, (which must be made) in 50 releasing the brakes of the car, will bring said lever directly opposite and simultaneously in contact with the heads of the two vertically-aligned movable-contacts 8, which will close the circuit through said lever, 55 and an alarm will be sounded as long as said lever is in a thrown-off position, or until the owner inserts his key 2 in the lock-casing 1 and moves said key to such a position as will break the circuit between 60 said movable contact 4 of said lock-casing and said fixed contact 5, after which the owner, or any authorized person, may drive the car without sounding an alarm. The said brake-lever 10 cannot fail to close the 65 circuit between the said two vertically-aligned contacts 8 during the movement of said lever from a brakes-applied to a brakes-released position, inasmuch as both of said contacts are normally in the path of said 70 lever.

I claim:—

An improved brake-lever circuit-closer for automobile theft signals, comprising a sector-plate; insulating-tubes embedded in said 75 sector-plate and arranged one above the other; movable contacts carried by said sector-plate in said tubes; a head or flange upon the outer portion of said contacts to prevent said contacts from being pushed too 80 far within said tubes; a shoulder or flange on the inner portion of said contacts to limit the outward movement of the said contacts; springs in said tubes for transmitting 85 current to said contacts, and urging the latter outwardly; and a brake-lever adapted to contact with the said contacts in said sector-plate simultaneously, substantially as described.

In testimony whereof, I have signed my 90 name to this specification in the presence of two subscribing witnesses.

DANA S. LEE.
